UNITED STATES PATENT OFFICE.

JAMES T. HAMBAY, OF PITTSBURG, PENNSYLVANIA, ASSIGNOR TO THE UNION SWITCH AND SIGNAL COMPANY, OF SAME PLACE.

SIGNAL-LINE COMPENSATOR.

SPECIFICATION forming part of Letters Patent No. 309,618, dated December 23, 1884.

Application filed February 15, 1883. (No model.)

To all whom it may concern:

Be it known that I, JAMES T. HAMBAY, of Pittsburgh, county of Allegheny, State of Pennsylvania, have invented or discovered a new 5 and useful Improvement in Signal-Line Compensators; and I do hereby declare the following to be a full, clear, concise, and exact description thereof, reference being had to the accompanying drawings, making a part of this specification, in which—like letters indicating like parts—

Figure 1 is a view in side elevation of so much of a signal-operating mechanism as is necessary to illustrate my present invention. 15 Fig. 2 is a detached view, to an enlarged scale, of the interlocking mechanism of Fig. 1, but with the front plate removed; and Fig. 3 is an edge view of the devices of Fig. 2 and of a portion of the upper end of the mechanism 20 connected therewith, but to one-half the scale of Fig. 2.

My present invention relates to that class of railway signaling apparatus in which, by a lever or other like movement, a railway-signal 25 at a greater or less distance is actuated or shifted, so as by one or the other of two different positions it may indicate "danger" or "safety," as the case may require.

As a means of making connection from the 30 lever or from the cabin or stand occupied by the operator to the signal, a wire or wire rope or other like device is employed, and as this is subject to elongation and contraction under variations of temperature, it is important, 35 especially where the distance is considerable, to provide some means by which such elongation, when it occurs, will be taken up automatically, and also by which contraction will be provided for. My invention is directed to 40 this end, and I accomplish the purpose by the use of a gripping mechanism, which, acting on the principle of a grapple, or like a pair of tongs, or on the ratchet-and-pawl principle, shall interlock with or be disengaged from 45 a suitable device connected with the signal. The signal motions may be as desired; but preferably, when the gripping mechanism is out of action, the signal, under the action of a weight or spring, goes to its normal or 50 "danger" position, and is shifted thence to a "safety" position only by the action of the

proper lever, transmitted through the gripping mechanism and through the wire or other connection.

Any suitable lever or other signal-shifting 55 mechanism may be employed; but for the purposes of illustration I have shown at A a portion of a Saxby and Farmer interlocking lever, such as is in common use, A' being its pivotal point. The wire a (or its known substitute) leads to the signal to be operated, and passes under the loose pulley P and over the loose pulley P', and is kept taut by a weight, W, which, however, should not be heavy enough to change the position of the signal 60 from what it otherwise would be. In the line of this connection I insert a rack-bar, c, toothed on one or both sides, preferably on both, or having its surfaces so shaped that it may be gripped or engaged by one or more 65 grappling devices, one form or construction of which is represented by the pawls c'. The latter are pivoted, as at c', in a box, B, and the latter is by a pair of straps, b, hung to the arm b' of the lever A. The rack-bar c passes 70 or plays freely through the box B, except when engaged by the pawls c', so that the wire a may elongate freely, its slack being taken up by the weight W, or may contract freely, 75 the weight W then rising. The pawls c', when 80 not otherwise acted on, are pressed into engagement with the rack-bar c by means of spring e and plungers e'; but to provide for throwing them out of their interlocking engagement with the rack-bar c, I employ a trip 85 device, which consists of two studs, d' d'', which are affixed to or made solid with a pendant rod, d, which latter may be secured to some fixed part of the cabin, as the floor or table A², it only being essential that it should be in 90 its proper position to throw the pawls out of engagement with the rack-bar when the latter has moved to such position as to bring or allow the signal to come to its reverse, or, say, 95 its "danger" position. Then when the signal is to be cleared the operator, by moving the lever A, draws upon the straps b, raises the box B so as to carry the pawls c' clear of the studs d', and then the springs e force the pawls into engagement with the teeth of the rack-bar c, 100 and then the rack-bar must move up with the pawls and box, and the wire a will be drawn

- in and the signal connected with its farther end will be correspondingly shifted. Reversal of the lever motion lowers the box B, and with it the rack-bar c, until the pawls c' engage the 5 studs d', as a result of which the pawls will be disengaged from the teeth of the rack-bar, and the line-connection from the weight W to the signal will be free to elongate or contract, as may result from variations of temperature.
- 10 Of course the rack-bar should be as long, or approximately as long, as the greatest ordinary variation in the length of the line-connection a, and the pulleys P P' should be far enough from its ends to admit of the operations described under variations of length, as 15 aforesaid.
- Instead of the rack and two pawls, a single-faced rack and one pawl may be employed, though in some respects less advantageously.
- 20 The vertical ribs s s of Fig. 2 are made solid with or as a part of the box B, and they perform the function of properly guiding the studs d', or of keeping them in place with reference to their action in tripping the pawls c', 25 as above described.
- The straps b may at their lower ends be connected with or be secured to plates n, by which to be bolted to the box B, or this connection may be otherwise, as desired.
- 30 I claim herein as my invention—

1. A toothed, serrated, or roughened bar, c, and a box, B, one arranged in the signal-line connection and the other connected with the lever movement, in combination with pawls c', pivoted to the box B, and adapted to engage 35 the bar c, and fixed tripping-studs d', substantially as set forth.

2. The box B, having one or more pawls, c', and springs e, in combination with bar c and stud or studs d', substantially as set forth. 40

3. A toothed, serrated, or roughened bar, c, arranged in the signal-line connection, and a box, B, connected with the lever movement, in combination with a pawl or pawls adapted to effect the locking of the box and bar, and 45 fixed tripping-studs located in position to disengage said pawls from the bar by contact with the pawls at or near one end of the traverse of the bar, substantially as set forth.

4. The combination of the pulleys P P', the 50 signal-line a, a bar, c, interposed therein between said pulleys, weight W, box B, with its pawls and springs, and rod d, with its studs d', substantially as set forth.

In testimony whereof I have hereunto set 55 my hand.

JAMES T. HAMBAY.
